UNITED STATES PATENT OFFICE.

JAMES M. O'BRYAN, OF PAYNEVILLE, KENTUCKY.

BARREL-TRUSS.

SPECIFICATION forming part of Letters Patent No. 258,944, dated June 6, 1882.

Application filed March 20, 1882. (No model.)

To all whom it may concern:

Be it known that I, JAMES M. O'BRYAN, a citizen of the United States of America, residing at Payneville, in the county of Meade and State of Kentucky, have invented certain new and useful Improvements in Barrel-Trusses; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to an implement designed for the purpose of drawing the staves of barrels snugly together to facilitate the application of hoops thereto, and is adapted to be used in barrel-factories and in warehouses 20 where hooped packages are stored when such packages have been bursted by the swelling of their contents, or when such contents as tobacco has cured, dried, or shrunken and it is desired to tighten the packages by the reapplication of hoops; and my invention consists 25 in certain devices and combinations of devices hereinafter fully described, and specifically set forth in the claims.

Figure 1 is a perspective of my device, and 30 Fig. 2 is a plan with the cover removed.

Like letters indicate like parts in all the figures.

A represents a portable crescent-shaped case provided with a central shaft, B, having 35 a ratchet, C, and crank D secured thereto. To the top E of the case is secured a pawl, F, adapted to act upon the ratchet and to be swung upon its pivot *f* away from the ratchet. The top is also provided with a suspension-hook, G, secured by a bail, h, and staples *i i*. The cover and its appendances is secured to 40 the case by screws J J. Through the perforation *b* in the shaft B is passed an endless cord, strap, or rope, K, which is coiled about said shaft at each side of the perforation *b* in 45 opposite directions, one portion passing through an opening, K', being guided by and upon the pulleys *k k'*, and thence on the outside of the case to and through an opening, K², at the 50 lower side and opposite end of the case, and is guided by the pulleys *k² k³* (in dotted lines) back to the shaft where it joins the other portion oppositely coiled thereon. The bearings

of the guide-pulleys *k k'*, *k² k³* are shafts *l*, supported in the cover and bottom of the case 55 and the bridge pieces or partitions M, one pair of said guide-pulleys being above and the other pair below the partitions, as shown in dotted lines at Fig. 2.

The operation of the device is as follows: 60 The rope is unwound from shaft B and thrown around a barrel, and the crank is turned, thus tightening the rope and drawing the staves together, the inwardly-curved side of the case resting against the side of the barrel, and, if 65 desired, the suspension-hook resting over the chines. When the rope is drawn sufficiently tight the pawl is thrown against the ratchet, and the barrel-staves are thus temporarily held together until the hoops are securely attached, when the process is repeated at other points on the barrel.

I am aware that circular portable truss-cases have been used; but the crescent-shaped case has the advantage that it can readily be 75 applied to a cask the staves of which are greatly expanded—as, for instance, when all the end hoops are removed—in which case either a cumbersome circular case must be used or preliminary compression of the expanded staves must be secured before such a case can be applied, whereas with a crescent-shaped case the rope can readily be put about the staves and the operation at once commenced.

Having described my invention and its operation, what I claim as new, and wish to secure by Letters Patent, is—

1. The portable crescent-shaped case A, provided with the central shaft, B, the ratchet and 90 pawl, and the rope K, wound in opposite directions on the shaft, the whole being combined, arranged, and operating substantially as shown and described.

2. In a barrel-truss, the combination of the 95 crescent-shaped case A, provided with the partitions M, shaft B, rope K, and pulleys *k k'*, *k² k³*, located in pairs on opposite sides of the partitions, substantially as shown and described.

In testimony whereof I affix my signature in presence of two witnesses.

JAMES M. O'BRYAN.
